MINING MACHINE

Original Filed Nov. 12, 1917

Patented June 30, 1925.

1,544,066

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed November 12, 1917, Serial No. 201,468. Renewed October 29, 1924.

To all whom it may concern:

Be it known that I, MORRIS P. HOLMES, a citizen of the United States, residing at Claremont, in the county of Sullivan and State of New Hampshire, have invented certain new and useful Improvements in Mining Machines, of which the following is a full, clear, and exact specification.

My invention relates to mining machines.

It has for its object to provide improved means whereby an internal part of a mining machine may be removed with facility through the bottom of the latter. A further object of my invention is to improve the cutter chain driving mechanism of such a machine. A still further object of my invention is to provide improved means whereby the cutter chain driving sprocket of a mining machine may be mounted within the frame in an improved manner whereby the bearings for the rotating parts may be maintained in accurate alignment and rendered readily accessible without removal of either the mining machine casing or shoe. A more specific object of my invention is to provide improved means whereby the bearing for the sprocket may be accurately aligned, whereby cramping of the bearings is prevented, and whereby the parts forming the bearings may be suitably enclosed in such a manner as to prevent the entry of dirt or the like into the same, at the same time that these parts are readily accessible through the machine shoe when desired, as for instance when it is necessary to replace a part which has become worn in service. These and other objects and advantages of my improved construction will hereinafter more fully appear.

In the accompanying drawings I have shown for purposes of illustration one embodiment which my invention may assume in practice.

In these drawings,—

Fig. 1 is a side elevation, partially in section, of a mining machine equipped with my improvement.

Fig. 2 is an enlarged detail sectional view showing the cap and sleeve removed.

Fig. 3 is a detail view, partially in section, showing the sleeve.

Fig. 4 is a detail sectional view showing the cap.

In this illustrative construction, I have shown a mining machine of standard con-

struction including a machine frame 1 slidably bodily on its bottom 2, herein in the form of a shoe, and carrying a motor 3 operatively connected through suitable gearing of any well known character, with a feed chain sprocket 13 adapted to cooperate with a suitable feed chain 14 in such a manner as to propel the machine about the mine in a well known manner, the connection of the gearing being controlled by a suitable clutch controllable by a controlling member 16. As in the usual construction, a cutter chain 17 revoluble about a suitable forwardly projecting cutter bar 18 is also connected at a point beneath the rear end of the machine to a cutter chain sprocket 19, which is in turn operatively connected to the motor 3 through suitable gearing. As shown, this gearing includes a gear 20 disposed concentric with and above the sprocket 19, and connectable therewith in a well known manner through the manipulation of a suitable clutch controlling member 22 operatively connected to clutch fingers 23 adapted to extend through suitable registering openings 24 in both the gear 20 and the sprocket wheel 19.

In my improvement, it will be observed that an upstanding member, herein illustrated in the form of a stud 25, is disposed coaxially within the sprocket wheel 19 and gear 20. As shown, this stud is provided with a reduced upper end 26 fixed to the frame 1 in any suitable manner, as by means of a pin 27, and is also provided at its lower end with a reduced portion 28 receivable in a suitable upstanding sleeve 29 on a shield or plate, herein a flanged cap 30, having its bottom disposed in the plane of the shoe 2 and its flange suitably attached to the frame 1 by attaching means, herein shown to comprise a plurality of screws 31. As shown, the gear 20 is also provided with an elongated hub 32, and a bearing sleeve or bushing 33 is disposed between the inner periphery of this hub and the surface of the stud 25 in such a manner as to form a bearing surface between the rotating gear and the stationary stud. In my improvement, the lower part of the gear hub 32 is also provided with an outer bearing surface 34 carrying a bushing 35 on which is revolvably mounted the hub 36 of the sprocket 19, the latter being held in position relative to the hub 32 by means of a lower clamping ring 110

37 clamped in position on the bottom of the hub 32 by means of a plurality of vertically disposed bolts 38. As shown, this bushing 35 is also preferably provided with a laterally extending annular flange 39 on its lower end adapted to underlie the under surface of the hub 36 and itself be supported on an annular flange 40 on the clamping ring 37. As illustrated, the latter is also preferably provided with an annular flange 41 on its lower surface adapted to rotate freely in a corresponding groove 42 formed on the frame 1. As shown, the bearing sleeve 33 is also provided with a laterally extending flange 43 on its lower end adapted to rest upon the upper ring of a suitable, herein a ball-type, thrust bearing 44 disposed around the flange 29 on the cap 30. Thus, obviously, by providing a suitable aperture 45 in the shoe 2 adapted to receive the cap 30 and located at a point beneath the stud 25 and the several bearings, not only may the smooth bottom of the shoe be preserved, but the parts may also be sealed by the cap 30 and means provided whereby, by simply removing the latter, the thrust bearing 44 and sleeve 33 may be withdrawn through the aperture 45 whenever desired. Obviously, also, by providing a threaded opening 46 in the cap 30 adapted to receive one of the screws 31 and permit the same to bear against the end of the stud 25, the cap may be removed at any time in spite of any tendency of the parts to stick.

35 In the operation of a machine equipped with my improvement, the power of the motor will obviously be transmitted in the usual manner through the different gearings described, to the feed chain driving sprocket 13 and the cutter chain driving sprocket 19, the connection of the parts being controlled by their respective clutch mechanisms. More specifically, it will be noted that while the latter sprocket is disconnected from its driving mechanism the gear 20 will obviously rotate on the bearing sleeve 33 and about the stud 25 within the then stationary sprocket 19, the thrust being taken on the thrust bearing provided. On the other hand, when the sprocket 19 is connected to its driving mechanism, the same will rotate with the gear 20, the two then turning about the stud and having the wear taken as in the previous instance by the sleeve 33 and the thrust taken by the thrust bearing. Thus, it will be observed that whether the parts 19 and 20 are connected or disconnected, the wear is taken upon the sleeve 33 and the thrust bearing, i. e., upon elements readily accessible and replaceable when desired by removable of the cap 30.

As a result of my improved construction, it will be observed that an exceedingly rugged and simple construction is produced in which no difficulty is experienced in lining

up the bearings of the several parts, due to the fact that the stud 25 is fixed to the frame, and that, further, later difficulty with cramping of the bearings is also obviated due to the fact that this stud is so supported in the frame and cap as to hold the parts accurately in alignment. Attention is also directed to the fact that due to my improved construction all the thrust of the parts is taken upon suitable thrust bearings, and that the same and the element which is subjected to the greatest amount of wear, namely the sleeve 33, are readily replaceable when desired, it only being necessary to remove the screws 31 in order to withdraw the cap 30, the ball bearing 44, and the sleeve 33. It will also be noted that this replacement may be made whenever desired without any necessity whatsoever for removing the machine frame or, as is ordinarily impossible, removing the shoe from the machine, it only being necessary to jack up the rear end of the machine in such a manner as to enable access to be had to the screws 31. In my improved construction, it will also be observed that the parts are effectually sealed by the cap 30 and the flange 41 in such a manner as to prevent the entry of dirt or the like into the bearings, and that this cap when in position is disposed flush with the bottom surface of the shoe in such a manner as to form a section of the shoe and permit the latter to slide freely on the mine bottom. These and other advantages of my improved construction will, however, be clearly apparent to those skilled in the art.

While I have in this application specifically described one embodiment which my invention may assume in practice, it will be understood that this form of the same is used for purposes of illustration and that the invention may be modified and embodied in other forms without departing from the spirit or the scope of the appended claims.

What I claim as new and desire to secure by Letters Patent is:

1. In a mining machine, a machine frame slidable bodily on its bottom during cutting, a cutter chain driving member thereon, a bearing for the latter preventing lateral displacement thereof, and means including an opening in the bottom of said frame and a removable closure therefor for enabling removal of said bearing through the bottom of said frame.
2. In a mining machine, a machine frame slidable bodily on its bottom during cutting, cutter chain driving mechanism above the bottom thereof including a plurality of bearings, and means including an opening in the bottom of said frame and a removable closure therefor for enabling removal of said bearings through the bottom of said frame.
3. In a mining machine, a machine frame,

- 5 a cutter chain driving member, a bearing therefor preventing lateral displacement thereof, and means including a removable shield carried by said frame whereby said bearing is accessible through the bottom of said frame.
4. In a mining machine, a machine frame, a shoe disposed beneath the same, a rotatable cutter chain driving member supported by said shoe, a bushing therefor, and means including a removable shoe section carried by said frame whereby said bushing may be removed through said shoe.
5. In a mining machine, a frame, a cutter chain driving member journaled thereon, a sleeve therefor, a thrust bearing therefor, and means including a centering member for one of said elements whereby said last mentioned elements may be removed through the bottom of said frame.
6. In a mining machine, a frame, a chain cutter driving member journaled thereon, a sleeve for said member, a thrust bearing for said member, and means including a removable cap carried by said frame and accessible from the bottom of said frame for holding said elements in position.
7. In a mining machine, a machine frame 30 slidable bodily on its bottom during cutting and having an aperture in its bottom, a stationary upstanding member thereon, a driving member on said member, a chain driving sprocket disposed concentrically therewith, and a bearing for certain of said elements removable through said aperture.
8. In a mining machine, a machine frame slidable bodily on its bottom during cutting and having an aperture in its bottom, a stationary upstanding member thereon, a driving member on said member, a chain driving sprocket disposed concentrically therewith, and a thrust bearing for certain of said elements removable through said aperture.
9. In a mining machine, a machine frame slidable bodily on its bottom during cutting and having an aperture in its bottom, an upstanding member on said frame, a driving member disposed concentrically therewith, a chain driving member rotatable with said driving member, and a plurality of bearing members for said elements removable through said aperture.
10. In a mining machine, a machine frame, an upstanding member carrier thereon, a driving member and a sprocket disposed concentrically with said upstanding member, a bearing sleeve between one of said elements and said upstanding member, and means including a detachable sleeve retaining member carried by said frame whereby said sleeve may be removed from the bottom of said frame.
11. In a mining machine, a machine frame having an opening in its bottom, an upstanding member carried on said frame, a rotatable cutter chain driving member on said upstanding member, a bearing therefor, and means including a plate carried by said frame and normally closing the opening therein for removing said bearing through the bottom thereof.
12. In a mining machine, a machine frame, a shoe disposed beneath the same, an upstanding member carried on said frame, a rotatable cutter chain driving member carried on said upstanding member, a thrust bearing therefor, and means including a removable cap carried by said frame whereby said thrust bearing may be removed through said shoe.
13. In a mining machine, a machine frame having an opening in its bottom, an upstanding member carried on said frame, a cap closing said opening and receiving the lower end of said upstanding member, a rotative chain driving member on said upstanding member, and bearings therefor accessible upon removal of said cap.
14. In a mining machine, a machine frame having an opening in its bottom, an upstanding member carried by said frame, a cap closing said opening and receiving the lower end of said upstanding member, a rotative chain driving member on said upstanding member, and bearings therefor removable through said opening upon removal of said cap.
15. In a mining machine, a machine frame having an opening in its bottom, an upstanding member carried by said frame, a removable cap closing said opening and receiving the lower end of said member, a rotatable chain driving sprocket on said upstanding member, and a plurality of bearings therefor centered by said cap.
16. In a mining machine, a machine frame, a detachable plate carried by the bottom thereof, a sleeve attached to said plate, an upstanding member projecting into said sleeve, a rotative member on said upstanding member, and a bearing between said upstanding member and rotative member, said bearings being removable upon the removal of said detachable plate.
17. In a mining machine, a machine frame, a detachable plate carried on the bottom thereof, a sleeve attached to said plate, an upstanding member projecting into said sleeve, a rotative member on said upstanding member, a bearing sleeve between said upstanding member and rotative member, and a thrust bearing between the rotative member and detachable plate.
18. In a mining machine, a machine frame, a detachable plate carried by the bottom thereof, a sleeve attached to said plate, an upstanding member projecting into said sleeve, a rotative member on said upstanding member, a bearing sleeve between said

upstanding member and rotative member, and a thrust bearing between said rotative member and detachable plate, said bearing sleeve and thrust bearing being removable upon removal of said plate.

19. In a mining machine, a mining machine frame, an upstanding member thereon, a rotative member on said upstanding member, a thrust bearing for said rotative member, and a single centering sleeve for said rotative member and thrust bearing disposed at the lower end of said upstanding member and removably carried by said frame to allow access to said bearing.

15 20. In a mining machine, a mining machine frame, an upstanding member carried thereon, a rotative member on said upstanding member, a thrust bearing for said rotative member; and a centering sleeve for 20 said rotative member and thrust bearing disposed at the lower end of said upstanding member and removably carried by said frame to allow access to said bearing.

21. In a mining machine, a machine frame, a stud having its upper end fixed thereon, a member rotatively mounted on the stud, a thrust bearing for the member, and a detachable centering sleeve for the member and thrust bearing disposed at the 30 lower end of said stud, said thrust bearing being removable with the centering sleeve.

22. In a mining machine, a machine frame including a portion adapted to rest on the mine bottom and having an aperture formed 35 in said portion, a closure for said aperture, and separate means adapted to cause separation of said closure from said aperture.

23. In a mining machine, a machine frame including a portion adapted to engage the 40 mine bottom and having an aperture formed therein, a closure member adapted to close said aperture, means adapted to hold said closure in position, and separate means to cause separation of said closure member 45 from said aperture.

24. In a mining machine, a machine frame including a portion adapted to engage the mine bottom and having an aperture formed in said portion, a closure member for said 50 aperture, a bearing to prevent lateral movement carried by said frame and said closure member, and means to enable removal of said bearing through said aperture.

25. In a mining machine, a machine frame, an apertured shoe disposed beneath said frame, a stud fixed to said frame, a driving member journaled on said stud, a chain driving sprocket journaled on said driving member, a thrust bearing receiving 55 the end thrust of said driving member, and 60

a removable cap carried by said frame holding said bearing and stud in position and disposed in the aperture in said shoe.

26. In a mining machine, a machine frame, a stud fixed at its upper end on said frame, a shoe disposed beneath said frame and having an aperture therein, a stud centering cap carried by said frame and removable through said aperture, a thrust bearing carried and centered by said cap, 65 a removable bearing sleeve carried on said stud, a driving member carried on said sleeve, and a chain sprocket journaled on said driving member, said thrust bearing and sleeve being removable upon removal 70 of said cap.

27. In a mining machine, a machine frame slidable on its bottom during cutting, a cutter chain driving member thereon, an 80 opening through the bottom of said machine in alinement with said cutter chain driving member, means for supporting and preventing lateral displacement of said cutter chain driving member, and closure means for said opening removable to enable removal of said first mentioned means through the bottom 85 of said frame.

28. In a mining machine, a machine frame slidable on its bottom during cutting, 90 a cutter chain driving member thereon, an opening through the bottom of said machine in alinement with said cutter chain driving member, means for supporting and preventing lateral displacement of said cutter chain driving member, and closure means for said opening removable to enable removal of said first mentioned means through the bottom 95 of said frame and constituting positioning means for said first mentioned means.

29. In a mining machine, a machine frame including a portion adapted to rest on the mine bottom and having an aperture formed in said portion, a closure for said aperture, and separate means adapted to cause separation of said closure from said 100 aperture in a direction outwardly from said frame.

30. In a mining machine, a machine frame including a portion adapted to engage the mine bottom and having an aperture formed therein, a closure member adapted to close said aperture, means adapted to hold said closure in position, and separate means to cause separation of said closure member from said aperture in a direction 110 outwardly from said frame.

In testimony whereof I affix my signature.

MORRIS P. HOLMES.
